UNITED STATES PATENT OFFICE.

ALEXANDER K. YOUNG, OF BOSTON, MASSACHUSETTS.

IMPROVEMENT IN BAND AND SKIRT-HOOP ATTACHMENTS.

Specification forming part of Letters Patent No. 36,253, dated August 19, 1862.

To all whom it may concern:

Be it known that I, ALEXANDER K. YOUNG, a citizen of the United States of America, and a resident of Boston, in the county of Suffolk and State of Massachusetts, have invented a new and useful Band and Skirt-Hoop Connection; and I do hereby declare the same to be fully described in the following specification, and represented in the accompanying drawings, of which—

Figure 1 denotes a side view of portions of a band and a skirt-hoop as united by my said invention. Fig. 2 is a horizontal section of the same. Fig. 3 is a side view of the clasp before being bent in the form in which it is prepared for being hooked into the band. Fig. 4 denotes a perspective view of the clasp as ready to be applied to the band. Fig. 5 is a top view of a portion of a skirt-hoop as ready for insertion into the clasp.

The object of my invention is to firmly affix the end or extremity of the skirt-hoop to a band extending down from the waistband of a lady's hoop-skirt, the said band with the metallic connections of the hoop being subsequently covered with leather or other suitable material sewed or otherwise properly affixed to them.

In the drawings, A denotes the band, B the clasp, and C the skirt-hoop. The connection consists of the clasp B and a knob or projection affixed to or extended from the skirt-hoop and to enter the clasp and operate to prevent detachment of the latter and the skirt-hoop.

In the drawings the end of the skirt-hoop C is exhibited as furnished with a projection, a. The clasp B is to be made from thin sheet flexible metal, and consists of a strip of the same about two inches in length and one-eighth of an inch in width, it being provided at one end of it with two projections or ears, b b, arranged as shown in Fig. 3. The said strip may be curved laterally for the purpose of strengthening it and better adapting it to cover that part of the skirt-hoop which is to be inserted within it. Furthermore, the strip so made is to be subsequently bent into the hooked form, as shown in Fig. 4, its two lips being bent upward, so as to stand with respect to the rest of the strip as exhibited in Fig. 6, which is an end view of the lips and strip. The clasp so made may be said to be provided with a tongue, d, which, in connecting the clasp to the band A, is to be passed through the said band so as to hook the clasp

thereto. In weaving the band it is usually formed tubular or with two thicknesses where it is to be attached to each skirt-hoop. Fig. 7 may be supposed to exhibit an edge view of a band so made, e e representing the two thicknesses, between which the band is open, although it is closed between them and the next two. The tongue is to be passed laterally through the two portions e e, and afterward it may be carried through a loop or portion, f, of one of them in manner as shown in Figs. 1 and 2, in which case the part f will serve to aid in maintaining the clasp in place. Next, the end of the skirt-hoop should be inserted between the parts e e and into the clasp, so as to rest therein in manner as shown in Fig. 2, after which the clasp should be firmly contracted upon the skirt-hoop and the band, and the two projections or ears b b should be bent down closely upon the tongue d, so as to rest on it and hold it in place in manner as shown in Fig. 1.

The great objection to the common skirt hoop and band connection (which consists simply in inserting the hook into the cavity between the parts e e of the band and connecting the woven covering of the skirt-hoop with the band by sewing them together) is the constant liability of detachment of the two. This is so great that sooner or later their separation is almost sure to take place; but by my improved metallic attachment or hooked clasp and knobbed hoop to be applied together and to the skirt-band, as described, the union of the hoop and band is rendered strong and durable.

I would remark that it is not necessary to my invention that the tongue d of the clasp should go through a loop, f, as described; but when so applied to the band in connection with being hooked into it the clasp will be better supported by the band. I therefore consider the carrying the clasp through the loop as an additional improvement in its application to the band.

I claim as my invention—

My improved band and skirt-hoop attachment, consisting of the metallic clasp B and the projection a, constructed, arranged together, and applied to the band and skirt-hoop, substantially as described.

ALEX. K. YOUNG.
